STOP POSITIONING MECHANISM FOR
TYPEWRITERSWalter T. Sagner, West Hartford, Conn., assignor
to Underwood Corporation, New York, N. Y., a
corporation of Delaware

Application April 28, 1950, Serial No. 158,809

16 Claims. (Cl. 197—63)

1

This invention relates to typewriting machines and more particularly to mechanism for adjusting carriage arresting stops, such as left and right margin stops, to desired positions by manipulations involving stop-shifting movement of the paper supporting carriage, without the operator ever laying hands directly on such stops.

Stop setting mechanisms of this general kind have been devised particularly for typewriting machines wherein the stops to be adjusted are not conveniently accessible.

The invention is closely related to copending application by the same inventor, Serial No. 101,739, filed June 28, 1949, and issued on April 7, 1953 into Patent No. 2,633,964, in that it is founded on principles of operation and control which are similar, and particularly also because certain mechanisms and features shown and described in said prior application, but not repeated herein, are advantageous also for use in connection with the present invention. Thus, for a fuller appreciation of the general usefulness of the invention featured herein, reference may also be had to the said prior patent.

It is an object of the invention to provide simple mechanism for efficiently effecting adjustments of stops by remote control, rapidly and reliably, through easy, substantially non-fatiguing, simple controlling actions on the part of the operator.

It is a further object of the invention to provide an efficiently manipulative margin manifesting device of rugged and simple structure enabling the settling of margin defining elements or stops conveniently by remote control actions through movement of the carriage and without reliance on weak springs for moving the stops.

It is moreover an object to provide an efficient margin manifesting device of the type stated, and particularly embodying a margin stop unlocking or releasing key or control which may be operated prematurely, before the positioning of a margin stop in an adjusting station against the counterstop; efficient, simple provision being made for the device to furnish a stop releasing action whenever the stop is brought into said setting station with operating force exerted on said key.

Additionally, it is an object of the invention to provide a simple device of the nature stated, which includes efficient margin manifesting means whereby concomitantly to unlocking action on the margin defining element or stop, the device will hold the stop stationary with respect to the member whereon the device is supported.

It is furthermore an object of the invention to

accomplish any or all of the above noted objects by means including simple devices on the margin defining elements or stops directly cooperative with means operable to release the margin stops.

Other objects of the invention will become evident in the light of the detailed description of the preferred embodiment of the invention which follows.

Figure 1 is a sectional front elevation showing a skeletonized typewriter carriage with margin stops thereon, and showing portions of a frame-supported stop releasing mechanism.

Figure 2 is a skeletonized, sectional right-hand side view of a typewriter showing some parts additional to the mechanism of Figure 1.

Figure 3 is a right-hand front perspective view substantially of the elements illustrated in Figure 1, the main body of the carriage however having been omitted.

Figure 4 is a fractional front view of certain parts shown in Figure 1, a key associated with the stop releasing mechanism having been depressed and a margin stop to be adjusted being moved bodily with the carriage toward a position for the stop releasing mechanism to have an automatic releasing action on said stop.

Finally, Figure 5 is a view similar to Figure 4, the margin stop however located in releasing station against the counterstop, and released through action on said key.

Having now particular reference to Figure 2, a carriage 15 includes two spaced end plates 16 connected rigidly by a rail 17. Said rail is guided to travel linearly between two parallel trackways 18 by use of anti-friction elements 19, the trackways constituting part of a stationary framework of the machine. The carriage includes a usual platen roll 21 for support of writing material. A complement of types are adapted to strike individually against the front side of the platen at a common printing point, as indicated by a type bar 22 shown in dot and dash lines. The carriage is urged constantly in leftward, that is, in letter-feed direction under the power of a

spring motor 23 having a usual draw band connection with the carriage, but a letter-feed escapement 25 of conventional design associated with an escapement wheel 26 is normally in control over the carriage to hold it in a letter-feed position against the urge of said spring motor 23. A vertically disposed shaft 27 operatively connects said escapement wheel 26 with a pinion 28, the latter being in mesh with a letter-feed rack 30 supported on and partaking of the movements

of the carriage. Said escapement 25 comprises a

rocker frame 33 carrying a dog 31 normally in carriage holding engagement with one of the teeth of the escapement wheel 26, such holding dog 31, in a usual manner, permitting, however, ready movement of the carriage rightwardly in carriage return direction against the urge of the spring motor 23. The rocker frame 33 supports also a stepping dog 34, and is pivoted on an axis indicated as at 35. By mechanism old in the art, each operation of a type bar 22, as well as each 10 operation of a word space key, not shown, results in a letter feeding step of the carriage through a rocking action imparted to the escapement 25. For positioning the carriage conveniently in any position desirable, it may be 15 provided with a usual carriage release control 36, which, if actuated, by means of a link 37 swings the rack 38 upwardly, free of the pinion 28, spaced arms 39 supporting the rack for upward swinging movement about an axis 40.

The normal limits of carriage travel are adjustably established by a left and a right margin defining element or stop, respectively numbered 44 and 45, which stops are adapted to cooperate with a counterstop 46, see particularly Figures 1 and 3. Said stops 44 and 45 are supported for adjustment in parallel to the direction of movement of the carriage, on a toothed bar 47 which at its ends is secured upon the opposite end plates 16 of the carriage. As best seen in Figure 3, each margin stop 44, 45 may constitute a block or body grooved as at 51 for sliding adjustment lengthwise of the bar 47. A lock 52 on each stop in the form of a vertically movable slide normally holds each stop in a specific stopping position along the toothed bar 47. Each lock slide 52 is accommodated in a vertically disposed slot 53 of its stop, and is retained for vertical sliding movement along the rear of said slots by the rear side of the toothed bar 47. Each of said slides 52 includes a forwardly reaching nose 54 for stop locking engagement upwardly in the notches 55 of the toothed bar 47. Compression springs 56 underlying heads 57 on the upper ends of the slides 52 bias the latter upwardly so that the noses 54 are normally in stop-locking engagement in the notches of the bar 47. The springs 56 are preferably seated in sockets provided in the stop bodies, as shown. It will thus be seen that adjustment of either stop 44, 45 entails movement of the appropriate lock slide 52 downwardly, and according to the invention such movement is effected under keyboard control, in an efficient manner, as will be brought out later.

The counterstop 46, see particularly Figure 2, comprises the upper end of an upright arm 58 which is disposed approximately mid-way between the sides of the machine, said counterstop 46 protruding upwardly through a rectangular perforation 61 in a top plate 62 of a small housing 63 constituting part of the framework of the machine. The counterstop arm 60 is at its lower end borne on a headed stud 65, the latter projecting from the rear of a cross member 66 of the framework. In order that the counterstop 46 may be displaced out of range of the margin stops 44, 45, it has a vertical slot where it is borne on the stud 65, and a spring 67, see Figures 2 and 3, normally urges the counterstop arm 60 bodily upwardly to the limit of 70 the stated slot. Another spring 68, see Figure 3, has a rightward action on the arm 60 for the counterstop 46 to lie normally to the right in the perforation 61. The left margin stop 44 is usually leftward of the counterstop 46, whereas the 75

right margin stop 45 is usually rightward thereof, each margin stop having a stop face 70 facing normally toward the counterstop 46.

In the course of typing a line, the carriage travels leftwardly, and if the right margin stop 45 travels sufficiently far, its stop face 70 will engage the counterstop 46 to displace it leftwardly in the perforation the equivalent of about a letter-feed space. Such displacement of the counterstop in a conventional manner, not shown, results in the operation of a line-lock mechanism, not shown, rendering further typing infeasible unless by operation of a margin release key, not shown, the counterstop is lowered to ineffective position. Carriage return movement is limited normally by engagement of the face 70 of stop 44 with the counterstop 46, but return movement beyond is possible if the counterstop is lowered as just stated. So that the carriage may be moved readily from without to within the traveling range defined thereby by the stops 44, 45, each such stop has a cam face 69 to ride over and depress the counterstop 46 temporarily out of the way.

Either margin stop 44, 45 is adapted to be adjusted by carriage movement after it is first brought into engaged relation with the counterstop 46 by carriage movement, and to this end a conveniently accessible control in the form of a key 74 is provided in the keyboard of the machine to actuate a device 75 for releasing action on the appropriate margin stop. Said device 75, see Figures 1 and 3, consists of a composite slide comprising an upper member 76 and a lower member 77 joined distensibly by two shouldered studs 78 projecting rearwardly from the slide member 76 for association in slots 80 provided in the lower member 77. A spring 81 stretched between the two members 76, 77 keeps the member 76 in a contracted, lowered relation on the member 77 for movement therewith normally as a unit. Said composite slide 76, 77, see particularly Figure 3, is guided for vertical movement in the framework of the machine, and to this end the top plate 62 is notched as at 81 to accommodate slidably the member 76, the latter retained at the front by a finger 82 reaching from the underside of the plate 62 and fastened to the housing 63. The slide member 77 at its lower end has a slot 83 for sliding accommodation behind the counterstop arm 58 on the stud 65. Below the plate 62 another plate 84 is provided on the housing 63 to afford an intermediate sliding support for the composite slide or device 75. A spring 85 associated with the slide member 77 urges the device 75 normally to the upper position seen in Figures 1, 2 and 3, wherein a forwardly projecting end of the lower shouldered stud 78 engages limitedly the underside of the plate 84.

When the left margin stop 44 requisite to an adjusting operation therefor is brought by carriage movement rightwardly against the counterstop 46, then the forward part of the nose 54 on such stop is posed in operational alignment with a release finger 86 provided on the upper member 76 of the stop releasing device 75. Similarly when the line end margin stop 45 is brought by carriage movement into carriage movement limiting engagement with the counterstop, then the forward part of the stop lock nose 54 is posed in operational alignment with another release finger 87 provided on the member 76. Either of the stops 44 or 45 with its nose 54 posed as stated is releasable by actuation of the key 74

resulting in a downward actuation of the stop releasing device 75. In such release, see Figure 5, the appropriate release finger, by pressing down on the forward part of the lock nose 54, displaces the lock slide 52 downwardly to ineffective position. The key 74 is borne on the forward end of a lever 83 having pivotal support at 90 and including an arm 91 for actuation of a leftwardly extending lever 92 having an arm overlying a pin 93 projecting rearwardly from the member 77 of the device 75. Said key 74 and associated lever 83 are at the right side of the machine and the lever 92 is disposed as shown in Figure 3 to transmit motion to the member 77 which is at the mid-portion of the machine. The lever 92 has pivotal support in a bracket member 94 rising upwardly from the cross bar 66. A spring 96 associated with the lever 83 urges the same to the normal position shown in Figure 2, and a comb 97 wherein the forward end of the lever is guided provides a normal position stop.

It is to be understood that the fingers 86, 87 of the stop releasing device 75 lie normally clear of the travelling paths of the stops 44, 45. When either of the fingers 86 or 87 at depression of the key 74, incidental to a stop releasing operation, descends on one of the lock noses 54 there is first some idle movement before contact. During such idle movement the appropriate releasing finger 86 or 87 enters into a notch afforded by two spaced cam elements 98 flanking the lock nose 54 on each stop. The stated notch constitutes a forward extension of the guide slot 53 for the stop lock element 52 and is preferably somewhat wider than the slot to accommodate a finger 86 or 87 of ample strength. It will thus be seen that as a first incident to the downward actuation of the device 75 the appropriate finger 86 or 87 enters into the stated notch, wherefore then the stop to be released is held stationary with respect to the frame by the stop releasing device. Incidental to completed downward operation of the device 75, see Figure 5, the stop lock 52 is placed in released condition and with the key 74 then still held operated, the released stop is adapted to be given the desired new adjusted position on its supporting rack 47 by movement of the carriage to whatever position the stop is hence desired to function, it being understood that meanwhile the stop is held at its releasing station by one of the fingers 86 or 87. When then the key 74 is released, the resultant restoration of the stop releasing device 75 to normal position causes the stop lock 52 to become re-applied to hold the stop in the new position on the carriage.

There is no assurance that an operator may not operate the stop releasing device 75 prematurely, that is, before a margin stop to be adjusted is placed by carriage movement in contact with the counterstop 46. According to the invention, efficient provision is made whereby an operator may depress the key 74 at any time before the actual stop adjustment is commenced, that is, before the carriage is moved while the margin stop to be adjusted is against the counterstop in its releasing station. At such operation of the key 74, the upper member 76 of the stop releasing device 75 in any event will be drawn downwardly positively by the spring 81. If the margin stop to be adjusted is at such time far removed from its releasing station against the counterstop, then the member 76 will move to its downward limit established by contact of a pin 100 thereon with the finger 82. Assuming for the moment that it

is the right margin stop 45 that is required to be adjusted, the necessary leftward movement of such stop to bring it into contact with the counterstop 46, causes the camming face 101 on the left camming element 98 of the stop 45 to ride underneath and past the releasing finger 87, see Figure 4, to lift it above the forward part of the lock nose 54 on the stop 45, into operatively aligned position therewith. During the lifting of the finger 87, the member 77 remains operated due to sustained operation of the key 74, while consequently the spring 81 is distended. As the notch formed between the adjacent cam elements 98 of the stop 45 becomes positioned directly underneath the setting finger 87, the power stored in the distended spring 81 will automatically cause the member 76 to assume its normal relation with respect to the member 77, that is the member 76 will move downwardly to release the lock 52 on the oppositely stationed margin stop 45, as shown in Figure 5. The procedure for thereafter adjusting the stop 45 is the same as before outlined, namely, with the key 74 held operated, the carriage is given the appropriate position wherein the stop is desired to be active in the future, and thereupon said key is released to cause the restoration of the stop lock to holding position.

Also for adjustment of the stop 44, the operator may depress the key 74 at any time before the actual stop adjustment is commenced. For example, as the key 74 is operated the stop 44 may be situated at the right of the setting finger 86. As the carriage 16 is moved to bring the stop 44 into left margin gaging position, that is into releasing station, a cam face 101 on the left-hand cam element 98 of such stop acts liftingly on the stop releasing finger 86 for resultant stop releasing action on the forward part of the lock nose 54, by power of the distended spring 81, just as the stop 44 arrives in releasing station. Obviously, with the key 74 still held operated, movement of the carriage will then result in an adjustment of the stop 45 similarly as explained with reference to the stop 44.

As has been stated hereinbefore, each of the stops 44, 45 is provided with two cam elements 98 which oppositely flank the lock noses 54. Due to the provision of the left cam element 98 on the left margin stop 44, such stop, while the stop releasing device 75 is held operated, may be moved with the carriage leftwardly to its stop releasing station from a position therebeyond. Obviously during such leftward movement of the carriage a cam face 101 on the left of the stop 44 will effect a temporary upward displacement of the member 76 by contact with the finger 86 thereon, and, as the lock nose 54 on such stop assumes a position directly underneath the finger 86, the latter will descend automatically resulting in the release of the stop lock. Under the just stated procedure the margin stop 44 rides idly over the counterstop 46 and, instead of being arrested by coaction with the latter, becomes stationary in its stop releasing station by the releasing finger snapping in the notch between the two cam elements 98. The released stop 44 consequently is then adjustable by carriage movement while the key 74 is still held depressed.

Also the margin stop 45 has two cam faces 101. The cam face 101 at the right on stop 45 serves similarly to the cam face 101 at the left on stop 44, namely the stop 45 may be brought to setting station from a position at the left of

the counterstop 46 and under operated condition of the device 75.

It will be perceived that the stop releasing device 75 is capable of releasing action on a stop 44 or 45 only at the appropriate time, whether the key 74 is operated prematurely or not, and that always when either stop 44 or 45 arrives at its releasing station, and the key 74 is operated, the appropriate stop will be released and rendered stationary with respect to the counterstop 46.

Obviously, if the key 74 is operated while a stop is near its stop releasing station, then one of the fingers 86 or 87 will clash upon one of the cam faces 101 and during completed operation of the key 74 the spring connecting the members 76 and 77 of the stop releasing device will be strained. If thereafter the stop, by carriage movement, is brought into its releasing station, with the key 74 still held depressed, the result will be the same as in the case where said stop was initially at a location far removed from the releasing station.

For most convenient adjustment of the stops 44, 45, the machine is preferably equipped with certain keyboard-controlled power devices disclosed in the stated copending application, Serial No. 101,739. Namely, to bring the stop 44 against the counterstop 46 preparatory to effecting its adjustment, a power carriage return device including a return key in the keyboard may be provided. For bringing the stop 45 similarly against the counterstop 46, a keyboard-controlled carriage tabulating device may be provided. Additionally, as featured in said application, the stops 44, 45, after location in their individual adjusting station, are preferably caused to be adjusted on the carriage, leftwardly or rightwardly by power devices which under control means provided in the keyboard are adapted to effect this by repeat power spacings of the carriage leftwardly or rightwardly according to requirement. By use of the stated keyboard-controlled power devices and in conjunction with the key 74 the stops 44, 45 may thus be efficiently power adjusted under keyboard control similarly as featured in said copending application where said stop was initially at a location far removed from the releasing station.

While it is advantageous and desirable to provide a yielding provision, such as the spring 81 in the operating train from the key 74 to the stop releasing member 76, such yielding provision is not to be considered essential. Obviously in the absence of such a yielding provision there would be effected a temporary restoration of the key 74 against finger pressure maintained thereagainst, the maintained finger pressure at arrival of the stop at its releasing station being resultant in automatic stop releasing action of the device on the stop lock nose 54.

While the form of mechanism herein shown and described is admirably adapted to fulfill the aims and objects of the invention, it is to be understood that the invention is susceptible of embodiment in various forms coming substantially within the scope of the claims which follow.

What is claimed is:

1. In a typewriting machine or the like, having a carriage member guided to travel on a frame member, adjustable arresting means for said carriage member, comprising, a stop mounted on one of said members for adjustment in parallel to the direction of travel of the carriage member,

and a releasable stop lock, a part on said stop operable substantially transversely to said direction for release of said stop lock, a device on the other member posed in a relation for stop releasing action on said part only in a particular position of the carriage member defined by the adjusted stop, and means on said stop associated for coaction with said device if the latter is operated and this is followed by movement of the carriage member to said particular position, to impart resultingly a movement to said device for the latter to assume a relation for stop releasing action on said part.

2. The invention set forth in claim 1, and means on said stop and said device brought into engagement at each effective stop releasing operation of said device to hold the stop stationary with respect to said other member, whereby adjustment of the stop on its supporting member may then be effected by movement of the carriage member.

3. In a typewriting machine or the like, having a carriage member guided to travel on a frame member, adjustable arresting means for said carriage member, comprising, a stop mounted on one of said members for adjustment in parallel to the direction of travel of the carriage member, and a releasable stop lock, a part on said stop operable substantially transversely to said direction for release of said stop lock, a device on the other member posed in a relation for stop releasing action on said part only in a particular position of the carriage member defined by the adjusted stop, a key adapted for operation irrespective of the prevailing position of the carriage member, means to operate said device by said key and including resilient motion transmitting means, said part being operable by said device only if the carriage member is in said particular position, and means on said stop associated for coaction with said device if said key is operated and this is accompanied by movement of the carriage member to said particular position, to impart resultingly a movement to said device straining said transmitting means and conditioning the device for stop releasing action on said part under power of the strained transmitting means automatically at arrival of the carriage member in said particular position.

4. The invention set forth in claim 3, and means to hold said stop stationary with respect to said other member at each operation of said device resulting in the release of said stop lock.

5. In a typewriting machine or the like, having a carriage member guided linearly on a frame member for opposite directional movements, means comprising a stop and a counterstop supported oppositely on said members to limit one directional movement of the carriage member, means to mount said stop on its supporting member for adjustment in parallel to the linearly guided carriage member, said mounting means comprising a releasable stop lock carried by said stop, said stop and counterstop in limiting said one directional movement of the carriage member placing the latter in a limit station defined by said adjustment stop, a key, a device on said counterstop supporting member operable by said key to release said stop lock, a part of said stop having connection with said lock and being in position for lock-releasing operation by said device only when the carriage member is in the limit station defined by said stop, said device idly operable in other positions of the carriage member, further means on said stop clear of the

unoperated device in all positions of the carriage and adapted for direct cooperation with said device if operating force is applied on said key and additionally the carriage member thereafter is moved to said limit station from a position short thereof, to transitorily restore and then release said device to operate on said part for a stop releasing operation thereof as the carriage member arrives at said limit station, and means to hold said stop stationary with respect to the counterstop at each stop releasing operation of said part by said device.

6. In a typewriting machine or the like, having a carriage member guided lineally on a frame member, a stop and a counterstop supported oppositely on said members to limit one directional movement of the carriage member, means to lock said stop releasably on its supporting member for adjustment in parallel to the lineally guided carriage member, said stop and counterstop in limiting one directional movement of the carriage member placing the latter in a limit station defined by the adjusted stop, a key, a stop releasing element on the counterstop supporting member operable by said key transversely of the carriage member, said stop having a part for operation by said element to release said stop locking means, and said part being operable only when the carriage member is in said limit station, and means carried on said stop for camming action on said element in the event the carriage member is moved to the said limit station with operating pressure applied on said key, to force automatically a restoring movement of said element placing it in position for stop-releasing operation on said part when the carriage member arrives in the limit station defined by said stop.

7. The invention set forth in claim 6, and means conditioned by operation of said element only if the carriage member is at the limit station, to hold the stop stationary with respect to the counterstop, whereby adjustment of the stop may then be effected by movement of the carriage member.

8. In a typewriting machine or the like, having a carriage member guided lineally on a frame member for opposite directional movements, means comprising a stop and a counterstop supported oppositely on said members to limit one directional movement of the carriage member, means to mount said stop on its supporting member for adjustment in parallel to the lineally guided carriage member, said mounting means comprising a releasable stop lock carried by said stop, said stop and counterstop in limiting said one directional movement of the carriage member placing the latter in a limit station defined by said adjusting stop, a device on the counterstop supporting member operable for releasing said stop lock, means to operate said device impositively, comprising a key and a resilient element, means on said stop for operation by said device only when the carriage member is in the limit station defined by said stop, and when operated releasing said stop lock, said device adapted for idle operation by the key in other positions of the carriage member, and means carried on said stop for camming action on said device if said key is operated when the carriage member is short of said limit station, to impart during movement of said carriage member to said limit station a restoring motion to said device straining the said resilient element, said stop carried means arranged to free said device

automatically for stop releasing operation by the strained resilient element at the arrival of the carriage member at said limit station.

9. In a typewriting machine or the like, having a carriage member guided to travel on a frame member, adjustable arresting means for said carriage member, comprising, a stop mounted on one of said members for adjustment in parallel to the direction of travel of the carriage member, and a releasable stop lock, a part of said stop operable substantially transversely to said direction for release of said lock, an element on the other member posed in a relation for stop releasing action on said part only in a particular position of the carriage member defined by the adjusted stop, and means on said stop at opposite sides of said part in the direction of carriage travel, associated for camming coaction on said element if the latter is operated and this is followed by movement of the carriage member in either direction to said particular position, to impart resultingly a restoring movement to said element for the latter to assume a relation for stop releasing action on said part.

10. In a typewriting machine or the like, having a carriage member guided to travel on a frame member, adjustable arresting means for said carriage member, comprising, a stop mounted on one of said members for adjustment in parallel to the direction of travel of the carriage member, and a stop locking device on said stop including a part actuatable thereon transversely to said direction to release said stop for adjustment, an element on the other member posed in a relation for stop releasing action on said part only in a particular position of the carriage member defined by the adjusted stop, and oppositely slanting cam elements on said stop flanking said part in the direction of carriage travel, for action on said element if the latter is operated and this is followed by movement of the carriage member in either direction to said particular position, to impart a restoring movement to said element for the latter at arrival of the carriage member in said particular position to assume automatically a relation for stop releasing action on said part.

11. The invention set forth in claim 10, said cam elements forming a notch therebetween whereto said element is adapted to enter when it is operated with the carriage member in said particular position, whereby the stop is then held stationary with respect to said other member.

12. In a typewriting machine or the like, having a carriage guided to travel on a frame, adjustable arresting means for said carriage comprising, a stop mounted on the carriage for adjustment in parallel to the direction of carriage travel, and a releasable stop lock, a part on said stop operable substantially transversely to said direction for release of said lock, a device supported on the frame and posed in a relation for stop releasing action on said part only in a particular position of the carriage defined by the adjusted stop, a key at the front of the machine, means including a motion transmitting spring to operate said device by said key impositively, and means on said stop associated for coaction with said device if the latter is operated and this is followed by movement of the carriage to said particular position, to impart resultingly a restoring movement to said device stressing said spring and conditioning said device for automatic stop releasing action on said part as said particular carriage position is reached.

13. In a typewriting machine or the like, having a carriage member guided to travel on a frame member, adjustable arresting means for the carriage member, comprising, a rack on one of said members extending parallel to the direction of travel of the carriage member and a stop adjustable to different positions along said rack and having a stop lock means releasably in engagement with said rack, a part on said stop having connection with said stop lock means and movable transversely of the rack to release said stop lock means, a device on the other one of said members for stop releasing action on said part transversely of the rack only in the particular position of the carriage member defined by the adjusted stop, means including a key to operate said device, said device being idly operable in positions of said carriage member short of that defined by said stop, and means on said stop cooperative with said device if the latter is idly operated by said key and thereafter under condition of operating force sustained on said key the carriage member is moved to the limit position defined by said stop, to effect a transitory restoration of the device and then to release it for reoperation as the carriage member arrives in the position defined by the adjusted stop.

14. In a typewriting machine or the like having a carriage member guided to travel on a frame member; means comprising a margin defining element supported on one of said members for adjustment in parallel to the direction of carriage member travel to manifest the travel of the carriage member to a predetermined margin position, means adjustable along with said margin defining element, comprising, releasable lock means for said margin defining element including a part operable substantially transversely to the direction of travel of the carriage member, and including means flanking both sides of said part in the direction of travel of the carriage member, a manipulative control, and an operator for said part supported on the other of said members and adapted to be operated by said control to enter between said flanking means to operate said part only if said operator and said part have a specific position of lateral registration, said flanking means including a ramp having control over said operator so that if by movement of the carriage member in one direction said operator and said part are given said specific position of lateral registration while pressure is and stands applied to said control, the said operator will effect automatically at the end of such carriage member movement an operation on said part to release said lock means.

15. In a typewriting machine or the like having a carriage member guided to travel on a frame member; means comprising a margin defining

element supported on one of said members for adjustment in parallel to the direction of carriage-member travel to manifest the travel of a carriage member to a predetermined position, releasable lock means adjustable along with said margin defining element and comprising, a part operable substantially transversely to the direction of travel of the carriage member, a device on the other of said members posed in a relation for lock releasing operation on said part if said part relatively to said device by positioning of the carriage member is brought into a specific position of lateral registration, and means associated for adjustment along with said margin defining element and adapted for coaction with said device to control said device to impart a lock releasing action on said part if said device and said part by carriage-member movement and under condition of operating effort applied on said device are given said specific position of lateral registration.

16. In a typewriting machine or the like having a carriage member guided to travel on a frame member; means comprising a margin defining element supported on one of said members for adjustment in parallel to the direction of carriage member travel to manifest the travel of the carriage member to a predetermined margin position, means adjustable along with said margin defining element, comprising, releasable lock means for said margin defining element including a part operable substantially transversely to the direction of travel of the carriage member, and including means flanking both sides of said part in the direction of travel of the carriage member, a manipulative control, an operator for said part supported on the other of said members and adapted to be operated to enter between said flanking means to operate said part only if said operator and said part have a specific position of lateral registration, and resilient means to operate said operator by said control, said flanking means including a ramp having control over said operator so that if by movement of the carriage member in one direction said operator and said part are given said specific position of lateral registration while pressure is and stands applied to said control, the said operator will effect automatically at the end of such carriage member movement an operation on said part to release said lock means.
